UNITED STATES PATENT OFFICE.

JOHN STANLEY WILSON, OF ANNANDALE, NEAR SYDNEY, NEW SOUTH WALES,
AUSTRALIA.

MEANS USABLE WITH MECHANICAL TELEGRAPHS FOR SHIPS.

Application filed September 13, 1922. Serial No. 587,898.

To all whom it may concern:

Be it known that I, JOHN STANLEY WILSON, a subject of the King of Great Britain and Ireland, residing at 255 Johnston Street, Annandale, near Sydney, New South Wales, Australia, have invented certain new and useful Means Usable with Mechanical Telegraphs for Ships, of which the following is a specification.

10 This invention relates to means which are usable in connection with mechanical telegraphs for ships; the object of the invention is to provide means whereby it will be ensured that the orders transmitted by 15 the pilot to the engineer through the operation of the telegraph will receive correct attention. Said means may be used for indicating to the engineer whether the orders transmitted to him from the pilot have been 20 correctly attended to.

The said means comprise apparatus associated with the telegraph order dial located in the engine-room and also with the control lever or the like for regulating the motion 25 of the engine; said means may also comprise independent signalling apparatus.

Referring to the accompanying drawings, Fig. 1 is a perspective view of the apparatus; Fig. 2 a front elevation of the apparatus with hinged lever at the head thereof; Fig. 3 a section on line 3—3 Fig. 2; Fig. 4 a section on line 4—4 Fig. 2; Fig. 5 a perspective view of the apparatus shown combined with means whereby a visible and 35 an auricular signal may be given to the engineer; and Fig. 6 is a detail front elevational view of the audible signal used in the construction shown in Fig. 5; Fig. 7 is a perspective detail view of the shutter; Fig. 8 is a plain view of the same and Fig. 9 is a substantially vertical sectional view taken through the shutter and associated parts.

With reference to Figs. 1 to 4, a recessed frame 1 is provided with a diaphragm 2. Either one of the pulleys 3 or 4 fixed to the sleeves 5 and 6 may be connected by a cord or chain to the spindle of the receiver pointer of the order dial located in the engine room. If the pulley 4 is so connected the other pulley is connected to the lever or the like for controlling the motion of the engine. In Fig. 5 the pulley 4 is shown connected by the cords 33 to the cords 65 connecting the receiver telegraph dial 66

to the pilot's telegraph dial, and the pulley 3 is also shown connected by the cords 30 to the shaft 34 upon which the engine control lever 67 is fixed. On both sides of the diaphragm 2 is a pivoted lever 7 which carries at its head a contact roller 8. Similarly on both sides of the diaphragm 2 are a pair of levers 9 and 10. The levers 10 have pivoted to their head one end of a reciprocable cam-lever 11. Such cam-levers contact respectively with rollers 12 carried on the bottom of sliding rods 13 (one for each cam-lever 11) which may be made to project through openings in the head of the frame 1 depending on the movements imparted to the cam levers 11 by the operation of the levers 9 and 10 and the lever 7.

Integral with the sleeves 5 and 6 respectively are arms 14 and 25 which respectively carry rollers 15 and 16. Such sleeves are rotatably mounted on a spindle 17 which is rigidly fixed to the diaphragm 2. The levers 7 are pivotally supported on pins 18 secured to opposite sides of said diaphragm. 80 Stop pins 19 affixed to the diaphragm 2 are provided for the levers 7 and 10. Leaf springs 20 and 21 serve to keep the levers 7 and 9 in normal position as shown in Fig. 2; such springs may be suspended from pins 85 22 attached to the diaphragm 2. One end of one of the levers 9 at one side of the diaphragm 2 is fixed to one end of the rotatable spindle 23; the opposite end of said spindle has fixed to it on the opposite side 90 of said diaphragm one end of one of the levers 10. The other lever 9 is fixed at one end to one end of a rotatable sleeve 24 whose other end has fixed to it one end of the other lever 10. The arrangement of the 95 levers 9 and 10 on the spindle 23 and sleeve 24 is shown in Fig. 4. Cover plates 31 may be provided for the frame 1 if required.

In operation, assuming the pulley 4 to be connected to the spindle or the pointer 100 dial located in the engine room which pointer is moved by the pilot operating the telegraph, the arm 25 will be swung either to the right or to the left by the pilot when operating the telegraph to communicate his 105 signals to the engineer; if it is moved to the left the roller 16 will be brought into contact with the lever 9 on that side of the diaphragm 2 on which the pulley 4 is located and such lever 9 will be moved side- 110

wardly against the pressure thereon of the spring 21. As such lever 9 is affixed to the spindle 23 (see Fig. 4) one of the levers 10 on the opposite side of the diaphragm 2 to which the pulley 4 is located will be moved in a direction opposite to that of said lever 9 and consequently the cam-lever 11 associated with said lever 10 will be moved in the direction of movement of said lever 10. During such movements of the levers 9 and 10 and the said cam-lever 11 the levers 7 and the other cam-lever 11 remain stationary.

As the sleeve 6 is associated with the pulley 4 and the other sleeve 5 is associated with the pulley 3 and the pulley 4 is assumed to be connected to the receiver pointer dial, if the engineer should by error (after movements have been communicated as above described to the said levers) swing the arm 14 so as to bring the roller 15 into contact with the lever 7 on that side of the diaphragm on which the pulley 3 is located whilst the roller 16 is still in contact with the lever 9 and is pressing it outwardly against the spring 21, the lower end of said lever 7 will also be pressed outwardly against the pressure thereon of the spring 20 and the roller 8 on said lever 7 will be caused to ride on the bottom of the cam-lever 11 on the side of the diaphragm 2 on which the pulley 3 is located. Such roller 8 when it is brought into engagement with the swelling 26 on the said cam lever 11 raises said lever and also raises simultaneously the sliding rod 13 in contact therewith through the roller 12. The sliding rod 13 on the side of the diaphragm 2 on which the pulley 4 is located is not, however, raised but remains stationary, consequently the engineer will have a visible indication by the upper end of the said rod 13 (which has been moved) being above the other rod 13 that he has given motion to the engine in a direction contrary to the order telegraphed to him by the pilot. The levers 9 may be arranged for "ahead" orders and the levers 7 for "astern" orders or vice versa.

Referring to Figs. 5 to 9, means are shown therein associated with the frame 1 and the lever 27 whereby a visual and an audible signal may be given to the engineer in case he should operate the control lever of the engine contrary to the instructions transmitted to him (on the receiver dial of the telegraph) from the pilot. In Fig. 5 the pulley 3 is assumed to be connected by the cords 30 and the chains 32 to the shaft 34 to which the control lever or the like of the engine is fixed and the pulley 4 is similarly connected by the cords 33 and chains similar to the chains 32 to the receiver pointer dial of the telegraph located in the engine room. The chains 32 are shown attached respectively to the shaft 34 and to the pul-

ley 3; one end of the chains 32 at one end of the cords 30 may be attached to lugs 35 on opposite sides of a collar 36 fitting the shaft 34 and detachably fastened thereto by means of a pinching screw 64. A pinching screw 37 also serves to connect the chains 32 to the pulley 3.

At one side of the frame 1 is a bracket 38 having pivoted thereto by a pin 39 a counterweighted lever 40; this lever has pivot- 75 ed to it one end of a link 41 whose other end is pivoted to the lever 27. Another bracket 42 extends from the head of the frame 1 and carries at its outer end a bell 43; said bracket also has attached thereto by means of pins 46 leaf springs 44 and 45 located on opposite sides of a pivoted striker lever 47 for the bell 43. Associated with said lever 47 is a push lever 48 whose outer end slightly overlaps the end 49 of the lever 47; 80 the forward end of said lever 48 is pivoted to the bracket 42 and its other end is pivotally connected to a lug 50 on the lever 27. Upon the upward movement of the lever 27 the lever 48 tilts the lever 47 against the pressure of the spring 44 and when said lever 48 passes the end of the lever 47 it (the lever 48) swings backward and in such backward movement again strikes the lever 47 and brings it into contact with the bell 95 43. The lever 47 subsequently returns to normal position whereby one of its sides will be in contact with the spring 45. Abutment pins 51 and 52 are provided on the bracket 42 for the springs 44 and 45. 100

Simultaneously with the audible signal conveyed to the engineer by the bell 43 the link 41 raises the lever 40 whose free end is connected by a pivoted link 53 to a drop shutter 54 carried in a casing within full 105 view of the engineer. The said casing is rigidly attached by means of lugs 56 thereon to a supporting pillar 57, and its face 55 carries two pins 58 which pins whilst serving to attach the face 55 to a guide plate 110 59 also serve to distance such plate from said face. Attached to the head of the shutter 54 is a slider 60 engaging the guide plate 59; said slider has affixed thereto a plate 61 to which the foot of the link 53 is 115 pivoted. To prevent the lever 40 and the shutter 54 descending too far the wire spring 62 carried on the bolt 63 attached to the bracket 38 may be provided. Wording such as "Wrong movement" or other suitable indicating words may appear on the face of the shutter 54. Return of the lever 40 to normal position as shown in Fig. 5 is effected by the return of the lever 27 to normal position also shown in said figure. 125

It will be understood that if either of the rods 13 is not operated through the engineer moving the shaft 34 to control movements of the engine in accordance with instructions transmitted to him by the pilot the co- 130

operating mechanism of the bell 43 and the shutter 54 will not be operated by the lever 27. Any upward movement of either of the rods 13 will, however, move the lever 27 and consequently the said bell and shutter signals will be given to the engineer.

The lever 27 and the pulleys 3 and 4 have been omitted from Fig. 1 of the drawings for the purpose of allowing certain parts of the apparatus to be clearly seen.

What I claim as my invention and desire to secure by Letters Patent is:—

1. Apparatus for mechanical telegraphs for ships comprising a frame, rotary means attached to said frame and to the receiver dial of the telegraph, rotary means attached to said frame and to the engine control lever, indicator apparatus, and a series of levers disposed in relation to said rotary means and operable by the latter, whereby, when said engine control lever is operated contrary to instructions conveyed by said dial, said indicator apparatus which is associated with said frame and levers will be operated and made visible to the engineer.

2. Apparatus for mechanical telegraphs for ships comprising a frame, a diaphragm in said frame, a shaft fixed to said diaphragm and projecting at either side thereof, separate sleeves on said shaft carrying projecting arms located on opposite sides of said diaphragm, fixed pulleys on said sleeves one of which is operatively connected to the receiver dial of the telegraph and the other operatively connected to the engine control lever, a rotatable spindle journaled in a rotatable sleeve carried by said frame, levers on the opposite ends of said spindle and respectively located on the opposite upper and lower sides of said diaphragm, levers on the opposite ends of said rotatable sleeve and respectively located at opposite upper and lower sides of said diaphragm, cam levers on the heads of the levers at the upper of the opposite sides of said diaphragm, pivoted levers on opposite sides of said diaphragm adapted to separately raise said cam levers when operated, and a pair of sliding rods on opposite sides of said diaphragm adapted to be raised by said cam levers when either of the latter is raised.

3. Apparatus for mechanical telegraphs for ships, in combination a frame, rotary

means associated with said frame and operatively connected to the receiver dial of the telegraph, said means carrying projecting arms being adapted to operate simultaneously separate levers fixed to opposite ends of a rotatable spindle and respectively located at upper and lower portions of said frame, other rotary means operatively connected to the engine control lever and carrying a projecting arm adapted to operate simultaneously separate levers fixed to opposite ends of a rotatable element and respectively located at upper and lower portions of said frame, and a pair of cam-levers pivotally carried on the levers located in the upper portion of said frame, said cam-levers being respectively adapted to be raised when a coacting lever of a pair of pivoted levers on said frame is operated through wrong movements imparted to said engine control lever and the said rotary means and levers associated therewith, and a separate sliding rod for each of said cam-levers on said frame either of which is adapted to be made to project from said frame when operated by the cam-lever associated therewith.

4. In apparatus for mechanical telegraphs for ships according to claim 3, the combination of a lever pivoted at one end to said frame, and adapted to be moved outwardly from said frame by movements imparted thereto by either said sliding rods for the purpose of operating visual and aural signal means.

5. In apparatus for mechanical telegraphs for ships according to claim 3, the combination with the projecting arms of said rotary means of rollers carried on the outer end of said arms, said rollers being adapted to be brought into contact with the levers arranged in the lower portion of said frame and also with the levers for operating the cam levers.

6. In apparatus for mechanical telegraphs for ships according to claim 3, the combination with said frame and with the levers arranged in the lower portion of said frame and with the levers for operating the cam levers, of spring means capable of allowing side swing of said levers and of returning said levers to normal position.

In testimony whereof I affix my signature.
JOHN STANLEY WILSON.
